UNITED STATES PATENT OFFICE.

WILLIAM McCLINTOCK, OF NEW YORK, N. Y.

SEWAGE-EJECTOR.

1,279,735.

Specification of Letters Patent. Patented Sept. 24, 1918.

Application filed December 29, 1915. Serial No. 69,222.

To all whom it may concern:

Be it known that I, WILLIAM McCLINTOCK, a citizen of the United States, and a resident of New York, county and State of New York, have invented certain new and useful Improvements in Sewage-Ejectors, of which the following is a specification, reference being had to the accompanying drawings, forming a part thereof.

10 My invention relates to improvements in ejectors which employ compressed air for the purpose of elevating and ejecting sewage automatically, and its object is to provide a simple and efficient device which 15 shall operate automatically and rapidly. A further object is to improve upon such devices as have been known heretofore, such for example, as that disclosed in Patent No. 911,321 issued to me February 2, 1909. 20 These and further objects and advantages of the present invention will appear in the following specification in which I will describe a preferred form of mechanism embodying the invention, the novel features of 25 which will be set forth in appended claims.

Referring to the drawings:

Figure 1 is a sectional elevation of a sewage tank and its connections, with which is shown in elevation, an ejector which embodies my invention.

Fig. 2 is a longitudinal section of the ejector.

Fig. 3 is a transverse section of the apparatus shown in Fig. 2 the section being 35 taken on the line 3—3 of the latter figure.

Fig. 4 is a transverse section on the line 4—4 of Fig. 2, and Fig. 5 is a similar section on the line 5—5 of the same figure.

Fig. 6 shows a detail of the construction, 40 this figure being an elevation of the actuating levers.

Like characters of reference designate corresponding parts in all the figures.

10 designates a closed tank or receptacle 45 into which sewage or water or other similar material is discharged from an inlet 11 through an inwardly opening check valve 12. This material is to be discharged in a manner which will be set forth fully herein 50 through an outwardly opening check-valve 13 and a discharge pipe 14.

Inside of the tank is a float 15 which is preferably provided with a filler cap 16, as shown, so that it may be partly filled with 55 water if desired, for the purpose of regulating its buoyancy. This float is movable

on a vertical rod 17 which is guided in the top of the tank and in a bracket 18 on which the float rests when the tank is empty. This rod is also movable vertically and is provided with fixed stops 19—19 by means of which it is actuated by the float.

The ejector valve comprises a casing 20 through which is a cylindrical bore in which is a piston 21. 22 is a solid piston rod which is either integral with or securely affixed to the piston. The other end of this piston rod is guided in a hole in an end cap 23 which closes the rear end of the casing 20. A narrow collar 24 is carried by the piston rod.

The other end of the casing is constructed to form a pressure chamber 25 over the outer end of which is a member 26 which is constructed to form at its inner end a valve seat in alignment with the cylinder in which piston 21 slides, and at its other end a pipe connection 27. The valve seat is closed by a puppet valve 28 which is connected with, but spaced from, the piston. A pipe 29 (Fig. 1) connected at the end 27 of member 26, communicates with the interior of the tank 10.

The casing 20 is constructed to form two threaded ports 30 below the chamber 25, either one of which may be closed by a plug 31 and the other connected with an air pressure supply pipe 32. This construction makes it easy to lead the supply pipe to the more convenient side of the device. These ports 30 are connected with passages 33 90 which lead into the opposite sides of the chamber 25 so that the pressure of the entering air does not force the valve 28 to one side and thus cause undue friction. Furthermore, these passages are placed as near 95 to the seat of valve 28 as possible so that the air entering splits on the puppet valve and causes but little longitudinal pressure upon this valve when it is open which might have a tendency to make it creep shut. When it 100 is closed, however the air pressure aids in holding it in its closed position as the area of the puppet valve 28 is somewhat greater than that of the end of the piston 21.

Within the casing 20 back of the piston is 105 the exhaust chamber which is separated from the pressure chamber by the piston. At this part the casing is constructed as shown in Fig. 5, to form two oppositely disposed threaded ports 34—34 larger than 110 ports 30, one of which is closed by a plug 35 and to the other is connected a pipe 36

which communicates with the pipe 29 and thus with the interior of tank 10. 37—37 are passages from the communicating ports 34 to the main cylinder on opposite sides 5 thereof.

Just forward of these passages is another somewhat narrower, which is shown in Fig. 2 of the drawings where it is designated by the reference numeral 38. This 10 passage extends around the cylinder and communicates with a transverse chamber 39, which terminates in two threaded ports similar to 34, one of which is closed by a plug 40 and to the other of which is connected an air discharge pipe 41.

The arrangement of all of the ports is similar to that already described, so that the pipe connections may be made on either side of casing 20, and the passages connecting 20 the ports with the cylinder are on both sides of the cylinder so that the air entering or leaving the cylinder does not tend to push the piston and its connected parts to one side or the other and thus cause undue friction.

Above the collar 24 the casing is constructed to form bearings for a transverse shaft 42 and a chamber 43 between the bearings, which chamber is closed by a removable cover 44. The part of shaft 42 between 30 these bearings is squared to fit a similarly shaped hole in a swinging member 45, the lower edge of which is recessed to fit over collar 24, and the upper part of which is provided with a knob or handle 46.

The other end of shaft 42 is supported in a stationary bearing 47 outside of which is a projecting lug 48, which is preferably an integral part of the shaft. The member which forms the bearing 47 is removably 40 supported in brackets 49 and the whole construction is such that when this member is removed the shaft 42 may be pulled out of the casing and inserted at will, it being only necessary in making such insertion to remove 45 the cover 44 and to hold the swinging member 45 by its knob 46 in proper position to cause the hole in this member to register with the squared part of the shaft.

On the outside of the bearing member 47 50 is rotatably supported a rock lever 50, one end of which passes through a slot-like eye in a top piece 51 affixed to the upper end of the rod 17, and the other end of which carries a weight 52 which counterbalances the 55 weight of the rod 17 and its attached parts. This rock lever is constructed to form two spaced shoulders 53—54.

55 is another lever which carries a weight 56. The lower end of lever 55 is forked and 60 its forked ends are bored to fit over the bearing member 47 on opposite sides of the rock lever 50. The part of this lever 55 which is directly above the bearing member is not high enough to clear the shoulders 65 53—54 but is so arranged as to be engaged

by one or the other of them as the rock lever is moved. Furthermore, that side of the forked portion of the lever 55 which is adjacent to the lug 48 is constructed to form spaced shoulders 57—58 which engage lug 70 48 as the lever 55 is moved.

I will now describe the operation of this apparatus. As the sewage collects in tank 10 the float 15 will rise on rod 17 until it reaches the upper stop 19, after which its 75 further upward movement will carry rod 17 and its top piece 51 with it. This will in turn raise the unweighted end of lever 50 until its shoulder 53 engages the adjacent end of lever 55, after which this too will 80 move about its pivotal support. The parts are so adjusted that before the tank 10 becomes filled, the weighted lever 55 will be moved past its vertical position after which the weight 56 will carry it over a sufficient 85 amount to cause its shoulder 57 to engage lug 48 and to rotate shaft 42 and swinging member 45 until the latter by its engagement with collar 24, moves piston 21 and its attached parts from the positions in which 90 they are shown in Fig. 2, to the left, a lost motion being provided for between the shoulders 53—54 and the part of lever 55 with which they engage and between the shoulders 57—58 and the lug 48. 95

This movement of the piston and its attached parts closes the port 38 and moves puppet valve 28 off from its seat. Compressed air is then admitted from the supply pipe 32 through the two ports 33—33 100 through chamber 25 and pipe 29 into the tank 10. The pressure of the air is great enough to eject quickly, the sewage through pipe 14.

When the level of the sewage is decreased 105 a sufficient amount to reverse the valve actuation already described, the piston 21 and its attached parts are moved back into the positions in which they are shown in Fig. 2. Now the compressed air is shut off and a 110 connection is open from the tank through pipes 29 and 36, valve passages 37, port 38 to outlet pipe 41. These pipes and ports are of larger capacity than the intake pipes and ports so that the discharge of pressure 115 is very rapid. Moreover, the parts are so set that the valve is shifted before all of the sewage is forced out of the tank as the expansion of the air before the pressure is exhausted is depended upon to force out the 120 last of the sewage.

In apparatus of this kind where the position of the float is constantly changing, it is important that the movement of the float shall not be imparted to the valve until the 125 float has reached the predetermined positions in its path of travel; in other words, that the valve should not be affected by minor fluctuations of the float or of the rock-lever. It is also important that the 130

valve motion itself be rapid and positive and its movements sensitive to control without being delicate in construction. All of these results are attained by the apparatus herein shown and described.

By the use of this apparatus a very rapid operation is possible and large quantities of sewage disposed of quickly. The fact that the swinging member is in the exhaust side 10 of the valve, the packing for shaft 42 need not be set up tightly and this has a further effect of making the valve sensitive in operation.

Furthermore, the fact that there is no 15 packing gland on the pressure side of the device, makes it possible to avoid air leakages which might occur when the apparatus is not in use, which leakages in former structures would cause the automatically controlled 20 air compressors which are commonly used to supply the air pressure, to start to compensate for this loss by leakage, causing unnecessary noise and loss of efficiency.

Structural modifications may be made 25 within the scope of this invention, and I intend that no limitations be imposed other than those indicated in the appended claims.

What I claim is:

1. In a sewage ejector, a pressure control 30 valve, and means for actuating said valve comprising a rock shaft and a rock lever, independent bearings for said shaft and for said lever in axial alinement with each other, and an intermediate weighted lever arranged 35 to be actuated by the rock lever and to actuate the rock shaft.

2. In a sewage ejector, a pressure control 40 valve, and means for actuating said valve comprising a rock shaft and a float-controlled rock lever, a member forming independent bearings for said shaft and for said lever in axial alinement with each other, and an intermediate weighted lever on said bearing member arranged to be actuated by the 45 rock lever and to actuate the rock shaft.

3. In a sewage ejector, a pressure control 50 valve, and means for actuating said valve comprising a rock shaft having one of its ends journaled in the valve, and a rock lever, a removable member forming a bearing for the other end of the shaft and an independent bearing for the rock-lever and an independent weighted lever pivotally supported on the part of the bearing member 55 which forms the bearing for the rock shaft, arranged to be actuated by the rock lever and to actuate the rock-shaft, said rock shaft being removable from the valve when said bearing member is removed.

4. In a sewage ejector, a pressure control 60 valve, and means for actuating said valve comprising a rock shaft having one of its ends journaled in the valve, a swinging member on said shaft within the valve, and a 65 rock lever, a removable member forming a

bearing for the other end of the shaft and an independent bearing for the rock lever and an independent weighted lever pivotally supported on the part of the bearing member which forms the bearing for the rock 70 shaft, arranged to be actuated by the rock lever and to actuate the rock-shaft, said rock-shaft being removable from the valve and from the swinging member when said bearing member is removed. 75

5. In a sewage ejector, a pressure control 80 valve having a casing, and means for actuating said valve comprising a rock shaft having one of its ends journaled in the valve casing, a swinging member on said shaft within the valve having a non-rotative connection with said shaft, and a rock lever, a removable member forming a bearing for the other end of the shaft and an independent bearing for the rock lever and an independent weighted lever pivotally supported on the part of the bearing member which forms the bearing for the rock shaft, arranged to be actuated by the rock lever and to actuate the rock-shaft, said rock-shaft being removable 85 from the valve and from the swinging member when said bearing member is removed, said valve casing having a removable cover over said swinging member.

6. In a sewage ejector, a pressure control 90 valve having a casing, a valve cylinder therein and a longitudinally movable piston valve in said cylinder, a rock-shaft journaled in said valve casing, a swinging member on said shaft within the valve casing having a non-rotative connection with said shaft and arranged when swung with the shaft to move said piston valve, threaded interconnected 95 ports on opposite sides of the valve casing, and passages from said ports to opposite sides of the valve cylinder arranged to be controlled by the piston valve, one pair of said passages being connected with a chamber formed within the valve casing having an outlet at the end of the valve casing, and 100 a puppet valve connected with said piston valve and arranged to control said outlet. 105

7. In a sewage ejector, a pressure control 110 valve having a casing and a longitudinally movable valve member therein, a rock shaft journaled in said valve casing, a swinging member on said shaft within the valve casing having a non-rotative connection with said shaft and arranged when swung with the shaft, to move said valve member, a 115 rock lever, a removable member forming a bearing for the other end of said shaft, and an independent bearing for the rock lever and an independent weighted lever pivotally supported on the part of the bearing member which forms the bearing for the 120 rock shaft, arranged to be actuated by the rock lever and to actuate the rock shaft; threaded interconnected ports on opposite sides of the valve casing and passages from 125 130

said ports to opposite sides of said valve member, said ports being arranged to be controlled by the valve member.

8. In a sewage ejector, a pressure control valve having a casing and a longitudinally movable piston valve therein, a rock shaft journaled in said valve casing, a swinging member on said shaft within the valve casing having a non-rotative connection with 10 said shaft and arranged when swung with the shaft to move said piston valve, a rock lever, a removable member forming a bearing for the other end of the shaft and an independent bearing for the rock lever and 15 an independent weighted lever pivotally supported on the part of the bearing member which forms the bearing for the rock shaft arranged to be actuated by the rock lever and to actuate the rock shaft, said 20 rock shaft being removable from the valve when said bearing member is removed; threaded interconnected ports on opposite sides of the valve casing and passages from said ports to opposite sides of said piston 25 valve and arranged to be controlled by said piston valve.

9. In a sewage ejector, a pressure control valve having a casing and a longitudinally movable piston valve therein, a rock shaft 30 journaled in said valve casing, a swinging member on said shaft within the valve casing having a non-rotative connection with said shaft and arranged when swung with the shaft to move said valve member, a float- 35 actuated rock lever, a removable member forming a bearing for the shaft, and an independent bearing for the rock lever and an independent weighted lever pivotally supported on the part of the bearing member 40 which forms the bearing for the rock shaft arranged to be actuated by the rock lever and to actuate the rock shaft, said rock shaft being removable from the valve when said bearing member is removed, said valve casing 45 having a removable cover over said swinging member and having threaded interconnected ports on its opposite sides and passages from said ports to opposite sides of said piston valve, said ports being 50 arranged and controlled by the piston valve,

one pair of said passages being connected with a chamber formed within the valve casing and having an outlet at the end of the valve casing, and a puppet valve connected with said piston valve of larger diameter than the diameter of the piston valve and arranged to control said outlet. 55

10. In a sewage ejector, a pressure control valve having a casing constructed to form a pressure chamber and a closed exhaust 60 chamber, a longitudinally movable piston valve in said casing separating said chambers, a valve seat at one end of the pressure chamber, a puppet valve, a solid reduced connection between the puppet valve and the piston valve, said longitudinally movable valve being arranged to coöperate with 65 said valve seat, a solid rod projecting from the opposite end of said longitudinally movable valve through the exhaust chamber, a collar on said rod, and a rock shaft co-operating with said collar and journaled in 70 said casing and passing through a part thereof which forms the exhaust chamber. 75

11. In a sewage ejector, a pressure control valve having a casing constructed to form a pressure chamber and a closed exhaust chamber, a piston in said casing separating said chambers, a valve seat at one end of the pressure chamber, a puppet valve, a solid reduced connection between the puppet valve and the piston, said puppet valve being arranged to coöperate with said valve seat, a solid piston rod projecting from the opposite end of said piston through the 80 exhaust chamber, and into the head of the valve casing, a collar on said piston rod, a rock shaft transverse to said rod journaled in said casing and passing through the part thereof which forms the exhaust 85 chamber, a packing gland for said shaft, and a swinging member on the rock shaft having a non-rotative connection therewith and said casing having a removable cover over the swinging member; said swinging member adapted to engage said collar to move the piston and its connected valve. 90 95

In witness whereof, I have hereunto set my hand this 27 day of December, 1915.

WILLIAM McCLINTOCK.
